UNITED STATES PATENT OFFICE.

MARION A. DOWNES, OF WEST ROXBURY, MASSACHUSETTS.

GAME.

Application filed March 9, 1923. Serial No. 623,963.

To all whom it may concern:

Be it known that I, MARION A. DOWNES, a citizen of the United States, and a resident of West Roxbury, county of Suffolk, and 5 State of Massachusetts, have invented an Improvement in Games, of which the following description, in connection with the accompanying drawings, is a specification, like characters on the drawings representing 10 like parts.

My invention relates to a game and particularly though not exclusively to one to be used in connection with phonographs.

My invention will be best understood 15 from the following description when read in light of the accompanying drawings showing one specific embodiment of my invention selected for illustrative purposes, while the scope of my invention will be more particularly pointed out in the appended claims.

In the drawings:

Fig. 1 shows an elevation of the submitted embodiment of my invention;

Fig. 2 is a section on the line 2—2 of Fig. 25 1 with parts omitted; and

Figs. 3, 4 and 5 show details.

Referring to the drawings I have indicated the phonograph at 1, this type of instrument as will be understood being provided with a turntable 3 which supports a 30 sound producing record 5, the turntable being supported on a mandrel 7 which projects above the turntable and centers the record therewith.

Above the record I have shown a base member 9 having a supporting plate 11 which projects beyond the member 9 so as to form an annular flange. As indicated in Figs. 2 and 5 the flange portion of the plate 40 11 is provided with openings 13 through which extend pins 15 rotatively supporting the spherical rollers 17. The plate 11 and base member 9 are provided with an axial opening 19 which receives the upper end of the mandrel 7 so as to center the base with the record. The rollers 17 rest upon the record and thereby permit relative rotation 45 between the record and the base 9.

Carried upon the base I provide a target 50 support which as herein shown consists of the four radiating vanes 21, these vanes being shaped in the semblance of a tree for which the base 9 provides the trunk. For accentuating the illusion when the vanes are 55 painted to represent branches and foliage each vane is provided with the openings 23.

Preferably I make the vanes 21 and base member 9 and its plate 11 of light weight material, as for example cardboard. The four vanes preferably are made from the two sheets indicated in Figs. 3 and 4, that shown in Fig. 3 having the slot 25 extending downwardly from the top of the sheet and that shown in Fig. 4 having the slot 27 extending upwardly from the bottom of the sheet. This, as will be understood by those skilled in the art, permits the sheets to be readily assembled with relation to each other in the position shown by Figs. 1 and 2. The upper portion of the base member 70 9 as indicated by Figs. 1 and 2 is provided with diametrical slots at right angles to each other which slots receive the four vanes 21 so as to hold the vanes and base member 9 in assembled relation. The bearing support 75 17 being located at separated points and below the center of gravity of the device, the latter is provided with a firm and substantial support.

In operation the frictional resistance of 80 the rollers turning on their pins exerts a force tending to rotate the base 9 with the record, while the vanes 21 meeting with air resistance tend to resist rotation, this resistance increasing with the speed, and in consequence the base 9 rotates at a much slower speed than the record, and by suitably proportioning the parts to vary the air resistance or friction or both the vanes may be made to rotate at any desired speed 85 relatively to the record. The vanes form a convenient support for targets herein indicated by figures of birds 29 which are provided with weighted tails 31 and a notch 33 allowing the figures to be loosely mounted or 90 perched upon the vanes.

Although I have described for purposes of illustration one specific embodiment of my invention it is to be understood that I am not limited thereby to its particular mechanical details, but that within the scope of my invention wide deviations may be made therefrom without departing from the spirit of my invention.

Claims:

1. The combination with a phonograph turntable, of a device to be rotated, said device having one or more vanes for causing atmospheric resistance to rotation thereof, and a roller support for said device for causing rotation of said turntable or of a record placed on said turntable to be transmitted

to said device and permitting relative rotation between said device and said turntable or record.

5. A device of the character described comprising a target support having one or more vanes for causing atmospheric resistance to rotation thereof, a base for said device adapted to be placed on a phonograph turntable or on a disk record placed on said 10 turntable, said base having means for centering it with the mandrel of said turntable and also having a plurality of rollers for resting on said turntable or record.

15. A device of the character described having one or more vanes shaped in the semblance of a tree, figures representing birds or the like loosely mounted on said vanes, and a base for said vanes carrying rollers for resting on a phonograph turntable or on a record placed on said turn-table.

20. A device of the character described having a plurality of radiating vanes shaped in the semblance of a tree, figures representing birds or the like loosely mounted on said vanes, and a base for said vanes carrying rollers for resting on a phonograph turntable or on a record placed on said turn-table.

25. The combination with a phonograph turntable, of a device to be rotated, means resisting rotation of said device, and a roller support for said device for causing rotation of said turntable or of a record placed 30 on said turntable to be transmitted to said device and permitting relative rotation between said turntable or record and said device.

35. The combination with a phonograph turntable, of a device to be rotated, means for resisting rotation of said device, said means increasing such resistance in response to increases in speed of said rotation, and a roller support for said device for causing 40 rotation of said turntable or of a record

placed on said turntable to be transmitted to said device and permitting relative rotation between said turntable or record and said device.

45. A device of the character described having one or more vanes shaped in the semblance of a tree, figures representing birds or the like loosely mounted on said vanes, a base for said vanes, a flange at the bottom of said base, and spaced rollers carried by said flange on radially disposed pins and adapted to rest upon a phonograph turntable or on a record placed on said turn-table.

50. The combination with a phonograph turntable, of a device to be rotated, vanes resisting rotation of said device, and a roller support for said device for causing rotation of said turntable or of a record placed on said turntable to be transmitted to said device 55 and permitting relative rotation between said turntable or record and said device.

55. An attachment for a phonograph, comprising a device to be rotated by the turn-table thereof, said device having provision for retarding its rotation, and driving connections for rotating the device from the turn-table but providing for its rotation at a lesser rate than that of the turn-table, said 60 connections comprising a plurality of separated bearing supports for said device.

65. An attachment for a phonograph, comprising a device to be rotated by the turn-table thereof, said device having provision for retarding its rotation, and driving connections for rotating the device from the turn-table but providing for its rotation at a lesser rate than that of the turn-table, said 70 connections comprising a bearing support for said device below its center of gravity.

75. In testimony whereof, I have signed my name to this specification.

MARION A. DOWNES.
